UNITED STATES PATENT OFFICE.

COLUMBUS C. ACTON, OF DETROIT, MICHIGAN.

FOUNTAIN-BRUSH.

1,085,839.

Specification of Letters Patent.

Patented Feb. 3, 1914.

Application filed February 15, 1913. Serial No. 748,520.

To all whom it may concern:

Be it known that I, COLUMBUS C. ACTON, a citizen of the United States, residing at Detroit, in the county of Wayne and State of Michigan, have invented certain new and useful Improvements in Fountain-Brushes, of which the following is a specification.

This invention relates to fountain brushes, and more especially to that class thereof in which a liquid is contained within the handle of the brush, and it has for one of its objects the provision of an improved article of this character comprising a chambered handle provided with a valve whereby the flow of liquid from the chamber will be controlled.

The invention has, furthermore, for its object the improved construction of the member in which the bristles are secured, in connection with improved fastening means whereby this member is held within the handle portion of the device.

Further objects of the invention will hereinafter appear and be particularly defined in the claims.

The invention has been clearly illustrated in the accompanying drawings, in which similar characters denote similar parts, in which—

Figure 1 is a central section of a brush embodying my invention. Fig. 2 is a horizontal section of line 2, 2 of Fig. 1, and Fig. 3 is a section similar to Fig. 2 showing the valve in its open condition.

While my invention is applicable to fountain brushes used for various purposes, I have illustrated in the drawing a shaving brush, the handle of which constitutes a reservoir for liquid soap, the handle being provided with a valve whereby this liquid may be permitted to flow into the bristle-portion of the brush, it being understood that water is used in connection with the liquid soap to form a lather by the manipulation of the device in the ordinary manner.

Referring to the drawings, 10 denotes the handle of the brush provided at its lower end with an annular flange 11 adapted to receive the bristle-holding member or plug 12 consisting substantially of a cylindrical body preferably made of hard rubber and having the bristles B secured therein in any suitable manner.

The liquid soap is contained within a chamber 13 of the handle, and the plug 12 has an axial perforation 14, the lower por-

tion 14' of which constitutes the discharge opening from which the liquid soap passes into contact with the bristles. The discharge of the soap through the perforation 14 is controlled by a valve or plug 15 slidable in a horizontal recess 16, the outer end of which is closed by a bushing 17 in screw-threaded engagement with the bristle plug 12. A spring 18 serves to hold the valve plug 15 normally against the bushing 17, in which position the flow of the liquid is interrupted. Means are provided for displacing the valve plug 15 to open the conduit 14, these means consisting substantially of a button 18' secured to the end of a stem 19 which is guided in the bushing 17 and in screwthreaded engagement with the valve plug 15, as clearly shown in Fig. 1. The plug 12 is held in its position in the device by a clamp-ring 20 in screwthreaded engagement with the flange 11 above referred to.

It will be noted that the button 18' is seated within a corresponding recess 21 provided therefor in the handle flange 11, and also that the bushing 17 is counterbored so as to receive a portion of the button where the latter is depressed to leave its outer crowned face flush with the outer surface of the flange. When the button 18' is in such position, the valve plug has uncovered the conduit 14, so that then the liquid may pass from the handle into the bristle-portion of the device.

While in some instances the button may be operated directly by the thumb of the operator, yet I have shown in the drawings a manually-operable annulus 25 supported for free rotative movement on the outside of the flange 11, this annulus being held in position longitudinally by a flange of the clamp-ring 20 above mentioned, the flange of which does not, however, bind the ring in position. This annulus is provided with a recess 25' into which the button head 18' may pass to close the valve, and the wall 25" of which serves as a cam to force the button 18' inward when the annulus is turned from the position shown in Fig. 2 to that shown in Fig. 3, in which case the liquid disposed back of the valve plug will be forced back into the reservoir through a passage 26 whereby a free run of liquid is established between the right hand end of the chamber 18 and the reservoir 13, so that consequently the parts are under a constant state of lubrication, and a vacuum between the end of the

plug 15 and the bottom of the recess 18 will be avoided. A similar passage 27 will permit access of the liquid to the left hand side of the valve plug 15.

5 From the above it will be understood that when the clamp-ring 20 is unscrewed, and the annulus 25 is in a position shown in Fig. 3, the latter may be readily removed from the handle portion, or more particularly 10 from the flange 11 thereof, whereupon the stem 19 with its button head may be removed from the valve plug, and the entire bristle-holding member or plug 12 is then free to leave the handle portion of the device 15 for cleaning or refilling. When re-assembling the parts, the just described operation is reversed. While in some instances it may be desired that the annulus 25 shall remain in position to hold the valve plug open, 20 yet I deem it preferable to provide means whereby said annulus will be automatically returned to position to permit the valve plug to be closed by its spring to bring the recess 25' into register with the button head 18', 25 these means consisting substantially of the spring 30 disposed within a recess 31 provided within the interior wall of the annulus, this spring being interposed between a shoulder 31' and an abutment member 30 shown herein as a screw 32 secured in the flange 11 through an aperture 33 provided for that purpose in the annulus 25.

Many changes may be made in the general organization as well as in the particular 35 construction of the component members of my improved device, without departing from the spirit of the invention, especially in the valve and its mode of operation.

I claim:

40 1. A fountain brush comprising a chambered handle having an enlarged recess, a bristle plug seated within said recess and having a longitudinal perforation, a valve disposed transversely of the plug and controlling the passage of material through 45 said perforation, and means for exteriorly operating said valve, and a ring in screw-threaded engagement with the wall of said

recess and engaging the outer end face of the plug for holding said plug in position in 50 the recess.

2. A fountain brush comprising a chambered handle having an enlarged recess in one end thereof, a bristle-plug seated within said recessed end and having a perforation, 55 a valve for controlling the passage of material through said perforation, and means for holding said plug in the handle and an annulus movably mounted on the recessed end of the handle and adapted to operate said 60 valve.

3. A fountain brush comprising a chambered handle having an enlarged recess in one end thereof, a bristle-plug seated within said recessed end and having a perforation, 65 a valve for controlling the passage of material through said perforation, and means for holding said plug in the handle and an annulus rotatably mounted on the recessed end of the handle and having a cam face adapted 70 to operate said valve.

4. A fountain brush comprising a chambered handle, a bristle-plug seated within the handle and having a perforation, a valve for controlling the passage of material 75 through said perforation, means for holding said plug in the handle, an annulus manually rotatable on the handle to open said valve, and means for returning said annulus to normal to close said valve. 80

5. A fountain brush comprising a chambered handle, a bristle-plug seated within the handle and having a perforation, a valve for controlling the passage of material through 85 said perforation, means for holding said plug in the handle, an annulus having a peripheral recess and manually rotatable on the handle to open said valve, and a spring in said recess for returning said annulus to normal to close said valve. 90

In testimony whereof I affix my signature in presence of two witnesses.

COLUMBUS C. ACTON.
